(57) **CLAIM**

We claim the ornamental design for a food container, as shown and described.

DESCRIPTION

FIG. 1 is a perspective view of a food container, showing our new design;

FIG. 2 is a perspective view of thereof;

FIG. 3 is a top plan view thereof;

FIG. 4 is a side view thereof, a front elevation view being the same, an opposite side and rear elevation views being mirror images thereof; and,

FIG. 5 is a bottom plan view thereof.

The broken lines in the figures illustrate the portions of the design that form no part of the claimed design.
